UNITED STATES PATENT OFFICE

GEORGE H. MCTEETERS, OF JOHNSTOWN, PENNSYLVANIA

ENGINE STOP

Application filed May 15, 1929. Serial No. 363,328.

This invention relates to engine stops and, while not limited thereto, relates more particularly to stops for use in stopping uniflow engines and similar devices, and has for its object the provision of a stop adapted to automatically stop the engine and prevent the engine running away, due to some unforeseen happening.

In the drawings—

10 Figure 1 is an elevation showing the engine stop of this invention applied to the cam shaft of a standard uniflow engine.

Figure 2 is a fragmentary elevation on a larger scale showing the stop construction in 15 driving position.

Figure 3 is a view similar to Figure 2 showing the stop in open or inoperative position.

Figure 4 is a sectional view through one 20 form of speed operated switch usable with this invention together with the circuit controlled thereby.

Referring more particularly to the drawings, the letter A designates a part of the engine housing and the letter B designates 25 the engine cam-shaft to which the stop of this invention is applied. The shaft B is divided into two parts 2 and 3 which are journaled in bearings 4 and 5 and are joined by a separable coupling or clutch C forming 30 a part of the stop mechanism of this invention.

Uniflow steam engines are standard machines and will not be shown nor described in detail. The uniflow engine is a double engine, taking steam in both cylinders at the same pressure. The intake valves are two poppet valves to each cylinder or four to the engine. The four valves are controlled by the cam-shaft B so that stopping of the part 40 of the cam-shaft B operating the intake valves of the engine will cause the immediate stopping of the engine.

The coupling or clutch C comprises coupling disks 6 and 7 fixedly mounted on the 45 adjacent ends of the parts 2 and 3, respectively, of the cam-shaft B. The disks 6 and 7 are provided with diametrically arranged slots 8 and 9, respectively, which are spaced around their periphery.

50 Connecting fingers 10 are pivotally mount-

ed in the slots 9 in the disk 7 and the forward ends of the fingers 10 are adapted to be removably engaged in the slots 8 of the disk 6 while the rear ends project away from the disk 7 along the shaft part 3. The rear ends 55 of the fingers 10 are connected together by coiled springs 12 which normally tend to pull the rear ends of said fingers inwardly against the shaft part 3.

A finger operating cone 13 is slidably 60 mounted on the shaft part 3 and is adapted to be moved under the fingers 10 to move them into the slots 8 and out from under the fingers 10 to permit the springs 12 to move the fingers out of the slots 8.

65 The cone 13 is provided with a circumferential groove 14 at its large end and the fingers 10 are each provided with a spring latch 15 adapted to enter the groove 14 when the cone 13 is moved under the fingers to 70 yieldably hold the cone in position.

A flange 16 is provided on the large end 75 of the cone 13 and pressure is adapted to be exerted against the flange 16 to cause the cone to move out from under the fingers 10.

A supporting standard 17 is mounted below the coupling C and serves to support a bell crank lever 18. The bell crank lever 18 is composed of a short and long arm and is pivotally connected adjacent the outer end of 80 its short arm to the standard 17 by a pivot pin 19. The short arm of the lever 18 has a roller 20 at its outer end adapted to engage the flange 16 on the cone 13 while the end of the long arm of the lever 18 is provided with a 85 weight 21.

The weight 21 is provided with an arm 21^a which projects through an opening 22 in a guide plunger 23 mounted for vertical movement in guide lugs 24 secured to the bearing 90 standard 25 of the bearing 5.

A suitable solenoid coil 26 is supported by a back-plate 27 secured between the guide lugs 24 and, when engaged, is adapted to attract a lever 28 which is hinged at one end, 95 as at 29, to the solenoid frame.

The guide plunger 23 is provided with a pivotal latch 30 adapted to be engaged over a lug 31 on the lower end of the solenoid frame. When the latch 30 is engaged over 100

the lug 31 it will hold the long arm of the bell crank lever 18 and the guide plunger 23 in raised position so that the roller 20 is out of engagement with the flange 16 of the cone 13.

In order to provide for automatically disengaging the latch 30 and the lug 31 so as to permit the long arm of the lever 18 to drop and force the short arm and roller 20 against 10 the flange 16 of the cone 13, a kick pin 32 is mounted in the lower end of the lever 28 and when the solenoid 26 is energized the lever 28 will be attracted and move the kick pin 32 inwardly to disengage the latch 30.

15 The solenoid 26 is adapted to have its energizing circuit completed through a standard centrifugal switch 35 operated by a pulley 36 connected to a pulley 37 on the driving part 3 of the cam shaft B by a belt 38. The 20 switch 35 is set to remain open until the shaft B is rotating beyond a predetermined maximum speed at which time the switch will automatically close and complete the energizing circuit to the solenoid coil 26.

25 The switch 35 may be of any desired construction, one form of which is illustrated and comprises a ball governor 35^a which operates when the speed of rotation exceeds a predetermined maximum to rock a lever 35^b 30 and close contacts 36^a to complete the circuit to the solenoid coil 26.

In operation, assuming that the driving part 3 of the cam-shaft B is coupled to the 35 driven part 2 by the coupling C and the apparatus is in operation, the coupling C will remain connected until the shaft B exceeds the predetermined maximum speed for which the switch 35 has been set.

When, for any reason, the engine exceeds 40 its predetermined speed, the shaft B, which is operated at the engine speed, will cause the switch 35 to operate and close the circuit to the solenoid coil 26, thus energizing said coil and attracting the lever 28. When the lever 45 28 is attracted, the kick pin 32 will strike the latch 30 and release said latch so as to permit the guide plunger 23 and the long arm of the lever 18 to fall. As the long arm of the lever 18 falls, the short arm will be rocked toward 50 the flange 16 on the cone 13 and the roller 20 will engage the flange 16 and force the cone along the shaft part 3 away from the coupling disks. As the cone 13 is started to move from under the fingers 10 of the coupling, the rear ends of the fingers will be 55 forced against the inclined cone face by the springs 12 and will aid in forcing the cone along the shaft part 3.

As the cone 13 moves from under the fingers 60 10, the fingers 10 will be rocked about their pivotal mountings so as to disengage their forward ends from the slots 8 in the disk 6, thereby breaking the driving connection between the shaft parts 2 and 3 and causing 65 the engine to stop.

If desired, various other switches, either hand or mechanically operated, may be provided for closing the energizing circuit to the coil 26 so as to provide various safety stops.

While I have shown and described one specific embodiment of my invention it will be understood that I do not wish to be limited thereto, since various modifications may be made without departing from the scope of my invention, as defined in the appended 70 75 claims.

I claim—

1. The combination with a two-part shaft arranged end for end in alinement, one of said shaft parts being a driving member and the other part being a driven member, of a separable coupling for said shaft parts, said coupling comprising a fixed coupling disk on the driving part of said shaft, a second fixed coupling disk on the driven part of said shaft, 80 said coupling disks having diametrically arranged slots in their periphery, yieldable connecting fingers pivotally mounted in the slots in said disk on said driving part of said shaft and adapted to enter the slots in said disk on the driven part of said shaft to form a driving connection between said disks, means tending to normally disengage said fingers from the slots in the disk on said driven part of said shaft, means for positively holding 85 said fingers in the slots in said disk on said driven part of said shaft, and means operable by the speed of the driving part of said shaft when said shaft exceeds a predetermined maximum speed for automatically rendering 90 95 said last named means inoperative.

2. The combination with a two-part shaft arranged end for end in alinement, of a separable coupling for said shaft parts, said coupling comprising a coupling disk fixed on 100 the adjacent ends of said shaft parts, said disks having slots in their peripheries, connecting fingers pivotally mounted in the slots in one of said disks and adapted to be engaged in the slots in the other of said disks 105 to form a driving connection, means tending to normally urge said fingers out of the position in which they form a driving connection, means for positively holding said fingers in position to form a driving connection, 110 and means operable by the speed of one of said shaft parts when said part exceeds a predetermined maximum speed for automatically rendering 115 said last named means inoperative.

3. The combination with a two-part shaft arranged end for end in alinement, of a separable coupling for said shaft parts, said coupling comprising a coupling disk fixed on the adjacent ends of said shaft parts, said disks 120 having slots in their peripheries, connecting fingers pivotally mounted in the slots in one of said disks and adapted to be engaged in the slots in the other of said disks to form a driving connection, said fingers projecting an 125 130

- appreciable distance along the shaft part beyond said disk to which they are pivoted, an operating cone slidably mounted on the said shaft part along which said fingers project, said cone being adapted to be moved under the projecting ends of said fingers to positively hold said fingers in position to form a driving connection, means tending to normally rock said fingers out of the position in which they form a driving connection, weight-operated means for moving said cone out from under said fingers, and electrically operated trip means for releasing said weight-operated means, and means operable by the speed of one of said shaft parts when said part exceeds a predetermined maximum speed for energizing said electrically operated trip means. 70
4. In combination, a two-part shaft having its parts arranged in end for end alinement, one of said shaft parts being a driving member and the other part being a driven member, a separable coupling for said shaft parts, said coupling comprising a fixed coupling disk on the driving part of said shaft, a second fixed coupling disk on the driven part of said shaft, said coupling disks having diametrically arranged slots in their periphery, yieldable connecting fingers pivotally mounted in the slots in said disk on said driving part of said shaft and adapted to enter the slots in said disk on the driven part of said shaft to form a driving connection between said disks, means tending to normally disengage said fingers from the slots in the disk of said driven part of said shaft, means for positively holding said fingers in the slots in said disk on said driven part of said shaft, and means for withdrawing said holding means. 80
5. In combination, a two-part shaft having its parts arranged in end for end alinement, one of said shaft parts being a driving member and the other part being a driven member, a separable coupling for said shaft parts, said coupling comprising a fixed coupling disk on the driving part of said shaft, a second fixed coupling disk on the driven part of said shaft, said coupling disks having slots in their peripheries, connecting fingers pivotally mounted in the slots in said disk on said driving part of said shaft and adapted to enter the slots in said disks on the driven part of said shaft to form a driving connection between said disks, said fingers projecting an appreciable distance along the driving part of said shaft beyond the disk on said shaft part, an operating cone slidably mounted on said driving part of said shaft, said cone being adapted to be moved under the projecting ends of said fingers to positively hold said fingers in position to form a driving connection, means tending to normally rock said fingers out of the position in which they form a driving connection, and weighted operating means adapted to be tripped to move said cone out from under said fingers to break said driving connection. 85
